CENTRIFUGAL PUMP STRUCTURE

Arthur C. Saxe, Columbus, Ohio, assignor to The
Jaeger Machine Company, Columbus, Ohio, a
corporation of Ohio

Application February 27, 1933, Serial No. 658,685

8 Claims. (Cl. 103—113)

My invention relates to centrifugal pump structure. It has to do, more particularly, with centrifugal pumps which are designed to be used in the removal of water from an excavation, although it is not necessarily limited thereto.

One of the objects of my invention is to provide a centrifugal pump which will be self-priming under practically all conditions of operation.

Another object of my invention is to provide 10 a self-priming centrifugal pump provided with a receptacle for priming fluid that will be of ample capacity and so disposed with relation to the various parts of the pump as to form a compact structure that may be economically manufactured.

Another object of my invention is to provide mechanism for controlling the self-priming operation which may be economically produced and which will operate with certainty and dispatch 20 in response to existing conditions in the suction line of the pump.

Another object of my invention is to provide a 25 centrifugal pump having a compartment for priming liquid together with a simple and effective means for preventing clogging of such compartment by mud or silt or other extraneous solid matter such as is liable to pass through a pump designed for the service indicated.

Another object of my invention is to provide 30 a self-priming centrifugal pump which has all of the parts thereof readily accessible for inspection or repair and on which the up-keep will be reduced to a minimum.

In its preferred form, my invention preferably 35 contemplates the provision of an impeller chamber of volute form which is eccentrically disposed within a larger and substantially cylindrical compartment that is adapted to contain priming liquid in sufficient volume that the pump will 40 always be ready for operation without special priming after any temporary stoppage to which it is likely to be subjected. The impeller of my pump is preferably of circular form with blades spaced sufficiently far apart to facilitate the passage therethrough of the material which the 45 pump is designed to handle.

In its preferred form, my centrifugal pump structure is provided with a discharge opening for delivering the fluid from the volute impeller 50 casing into the priming fluid compartment at the base thereof, and it is also provided with a discharge opening from the priming fluid compartment for the discharge of the liquid therefrom. It is further provided with a suction chamber mainly disposed within the priming fluid com-

partment and connected at one end to the interior of the impeller chamber substantially along the axis thereof and connected at its other end to the suction line which may be disposed in the excavation from which the liquid is to be pumped.

The suction chamber of my pump structure is provided with a passageway leading from the priming liquid compartment into the interior of such suction chamber. Operating in conjunction with this passageway, there is provided a controlling valve in the form of a plate which, when open, partially projects into the path of the liquid issuing from the delivery orifice of the impeller chamber and maintains this position as long as the velocity head of the liquid being drawn through the suction line and delivered through such impeller casing orifice is below a selected rate. This plate valve is initially movable towards closed position by the occurrence of the proper velocity head and is finally movable into position to substantially close the priming fluid passageway by the hydrostatic action of the water within the priming liquid compartment plus the suction within the suction chamber of the pump.

The preferred embodiment of my invention is shown in the accompanying drawing wherein similar characters of reference designate corresponding parts and wherein:

Figure 1 is a perspective view partially broken away, of my centrifugal pump structure.

Figure 2 is a vertical transverse section of the structure shown in Figure 1.

Figure 3 is a section taken on line 3—3 of Figure 2.

Figure 4 is a perspective view of my centrifugal pump structure assembled.

In the drawing, the exterior casing of my pump is shown at 1. This exterior casing is provided on one side, adjacent the top thereof, with an intake port 2 under the control of a check valve 3 and designed for connection to a suction line 4 that may, if desired, be provided at its lower end with a sand strainer 4a. The casing 1 is further provided with a discharge port 5 disposed in the top of such casing.

By reference to the drawing, it will be seen that the impeller chamber, which I utilize and which is designated 6, is eccentrically disposed within the casing 1. It is of volute form and its outer wall is formed by the side wall of the casing 1. It is of considerably less width than this casing and is located more closely adjacent to the base than to the top of the casing.

This impeller chamber is provided with a dis-

55

charge outlet 7 which is located at the bottom of the priming liquid compartment which is also disposed within the casing 1. It is further provided with a jet opening 8 in its inner side wall for the discharge of liquid therethrough. Both the discharge outlet 7 and the jet opening 8, being disposed at the base of the priming liquid compartment, will normally operate to undercut and stir up any mud or silt or debris that has settled in the priming liquid compartment or that may tend to clog this compartment.

Disposed within the volute impeller chamber is a circular impeller 9 having a plurality of widely spaced blades 10. This impeller is adapted to be rotated within the impeller chamber through the medium of a shaft 11 by means of a motor 12 which may be of any desired type.

The peripheral wall of the impeller chamber is continued, in a direction opposite to the direction of rotation of the impeller, past the discharge outlet 7 to form a blade 6' which extends inwardly a considerable distance from the discharge outlet. This blade 6' is provided for a purpose which will be hereinafter fully explained. The blade 6' is so disposed that the outer ends of the blades of the impeller will just barely pass such blade without interference therewith. It is important, as will be later understood, for the outer ends of the impeller blades to pass very close to the inner surface of the outer extremity of the blade 6' when the impeller rotates. Therefore, the outer end of the blade 6' is provided with a raised flat portion 6a. This flat portion is first made fairly high and is machined down to such an extent that it will lie very close to the outer ends of the impeller blades when they move past it. The outer surface of the outer end of each of the impeller blades 10 is substantially flat so that it will cooperate with the flat raised portion 6a of the blade 6' and will pass very close to such portion. In case a smaller impeller were used, the blade 6' would be disposed closer towards the center of the impeller chamber in order that it would lie close to the outer portion 48 of the impeller.

The priming liquid compartment may be generally designated 13. A portion of it is disposed above the impeller chamber and a portion of it is disposed along one side thereof, as at 14. It is at all times in communication with the discharge pipe through the discharge outlet 5 of the casing. When the pump is fully effective, most of the water passes from the discharge outlet 7 of the impeller chamber upwardly along the wall 15 of the priming fluid compartment and thence, out through the outlet 5, as illustrated by the heavy black arrows of Figure 3. A portion of the water, however, passes by the outlet 5 in the direction indicated by the light arrows and is circulated 60 within the priming liquid compartment to prevent settling of the mud and silt and assist in preventing clogging of the pump.

While this circulation is desirable, it should not be too violent. Otherwise, the violently circulated water may tend to entrain air and gas during the priming period and, by conducting it into the priming liquid passageway, defeat or tend to defeat the priming action.

Too violent a circulation of the liquid within the priming liquid compartment is prevented by the form and location of the suction chamber 16 which, in addition to its other functions, serves as an obstruction or baffle across that portion of the priming liquid compartment which is disposed at one side of the impeller chamber and

which, therefore, slows up the circulation of the water in the priming liquid compartment.

This suction chamber 16 communicates at its upper end with the intake port 2 and is provided adjacent its base with an outlet 17 which is of circular form and leads substantially axially into the impeller chamber. As illustrated in Figure 3, the suction chamber is substantially of rectangular form and is provided in its base with a priming liquid passageway 18, through which priming liquid may pass from the priming liquid compartment into the suction chamber and thence into the impeller chamber.

Under certain conditions, I may so construct my pump that the suction chamber 16 is extended to a higher level. Thus, the height of this suction chamber may be made sufficiently great to enable me to dispense with the provision of a check valve in the suction line and, at the same time, insure that the liquid from the priming liquid compartment will never be siphoned out of the suction chamber and into the suction line.

The priming liquid passageway 18 may be formed within a sleeve 19 projecting through the base of the suction chamber and it preferably leads into an elbow pipe 20 which directs the priming liquid towards the opening 17 and into the impeller chamber, thereby guiding it away from the intake port 2.

The means for controlling the priming fluid passageway 18 takes the form of a plate 21 which is hingedly secured to the base of the suction chamber by means of a rubber hinge 22. When this plate is in lowered position, as shown in full lines in Figure 3, the passageway 18 is open to permit free flow of the priming liquid from the priming liquid compartment into and through the elbow pipe 20 and thence to the suction chamber and interior of the impeller casing. When this plate is in raised position, as shown in dotted lines in Figure 3, it covers the passageway 18 and substantially stops the flow of priming liquid therethrough, although a relatively small aperture 23 through the plate 21 aligns with the passageway 18 so that the hydrostatic force of the water which holds the valve closed is neutralized somewhat to facilitate automatic opening of the valve when pump operating conditions necessitate priming.

As shown in Figure 2, the plate 21 is provided with a laterally projecting toe 24 which projects partially across the discharge outlet 7 of the impeller chamber when the plate 21 is in lowered position but which is substantially out of the path of direct flow of the water from the outlet 7 of the impeller chamber to the outlet 5 of the casing when the plate is in position to substantially close this priming water passageway 18.

The plate 21 is further provided adjacent its end with a weight 25 which is preselected with relation to the velocity head considered desirable as a condition precedent to the discontinuance of the priming action. This weight serves the dual function of predetermining this velocity head at which priming shall cease and insuring the automatic opening of the valve when priming is necessary.

In the operation of this plate valve, starting with the plate in the full line position shown in Figure 3, the starting of rotation of the impeller 11 will draw priming liquid through the passageway 18 and thence into the impeller chamber and through the discharge outlet 7 of the impeller chamber back into the priming liquid

compartment and again through the passageway 18. This circulation of the priming liquid will continue and the plate valve will remain immovable in open position as long as there is an undesirable proportion of air mixed with the water in the suction line of the pump with the air rising to the surface of the liquid in the priming liquid compartment and being thereby eliminated from the water flow. However, as soon as the predetermined velocity head exists in the suction line and is reflected in the velocity head at the discharge outlet 7 of the impeller chamber, the closing movement of the valve 21 is initiated by the pressure of the liquid against the toe 24 of the valve plate. This results in a rapid upward swinging of this plate to a position at which the hydrostatic pressure of the liquid in the priming liquid compartment and the suction effected through the passageway 18 become effective to complete the closing of the valve and the substantial discontinuance of supply of the priming liquid through such passageway to the impeller. Whenever the pump is stopped or whenever the velocity head of the liquid flowing therethrough drops below the predetermined minimum, the plate 21 will swing downwardly to completely uncover the passageway 18, so that the priming liquid will be free to pass therethrough for priming.

When the plate 21 is in closed position, it will be noted that the hydrostatic force of the water in the priming compartment will be exerted over the entire lower surface of the plate. This force will also be exerted over the entire upper lower surface of this plate with the exception of the very small area directly below the passageway 18. Thus, when the plate 21 is in closed position, as indicated by the dotted lines in Figure 3, it will be substantially hydrostatically balanced but will be slightly out of balance due to the fact that the hydrostatic pressure does not act on the small area of the upper surface of the plate which is directly below passageway 18. Thus, there is a slight hydrostatic unbalance which tends to keep the plate 21 in closed position. This force is aided by the suction force which also tends to keep the plate in position. However, the weight 25 is sufficient to overcome this slight unbalanced condition just as soon as vacuum is broken and the velocity head of the water discharged from the impeller chamber drops below a predetermined degree.

When the priming stage is completed, the continued operation of the pump results in drawing the liquid from the excavation through the suction line 4 and inlet 2 past the check valve into the suction chamber 16. From this suction chamber, it passes through the opening 17 into the impeller chamber and is discharged therefrom mainly through the discharge orifice 7. The major portion of the water so discharged passes directly to and through the discharge outlet 5, as indicated by the heavy black arrows, and thence through provided discharge pipes to any selected point. A portion of the liquid discharged from the discharge orifice 7, of the impeller casing passes on beyond the outlet 5 as indicated by the light black arrows and circulates over and around the impeller chamber to assist in preventing settling of mud and silt or other debris within the priming liquid compartment. The location of the discharge orifice 7 of the impeller chamber at the base of the priming liquid compartment causes the liquid discharged from such orifice to undercut and stir

up any mud, silt or other debris that may have settled or tended to settle in the base of such compartment. The liquid discharging from the side of the impeller chamber through the jet opening 8 further contributes to this undercutting and stirring of any material in the base of the priming liquid compartment.

The purpose of the blade 6' is to strip the air and water from the impeller especially during the priming action, in order that the priming action will be more efficiently and quickly carried out. When the impeller rotates it throws water outwardly therefrom, due to centrifugal force, and this water will tend to drag air along therewith which will accumulate in and around the impeller. If it were not for the blade 6', this air would be carried around with the impeller again and would thereby cut down the efficiency of the impeller and delay the priming action. However, because of the blade 6', the air being carried around by the impeller will be stripped therefrom by the blade 6' and will be caused to pass with the water out through the discharge outlet 7 of the impeller chamber. Since the outer ends of the blades of the impeller will be very close to the raised portion 6a of the blade 6' when they pass it, there will be very little air that will pass this point and will be carried back into the impeller chamber. Thus, the priming operation can be much more quickly and effectively carried out.

It will be seen from this that I have provided a centrifugal pump structure embodying a pump per se and a self-priming apparatus of extremely simple construction which can be obviously manufactured for a minimum of cost. It will also be apparent that the self-priming apparatus of my invention will permit of a continuous and uninterrupted feed of priming liquid to the pump impeller until the predetermined proper velocity head of liquid is passing through the pump, at which time, the supply of priming fluid to the impeller chamber will be automatically discontinued and the pump will then start to effectively perform its main duties. Moreover, if during the operation of the pump conditions arise which render further priming necessary, this will be taken care of automatically and with dispatch.

In the priming operation, it will be noted that the priming fluid which passes into the suction chamber is guided by the elbow 20 away from the check valve 3 and directly into the impeller chamber, so that danger of the priming liquid passing accidentally back into the suction line is precluded. Moreover, the spray of liquid thus directed towards the opening into the impeller chamber entrains air and assists in exhausting the air from the suction chamber and the suction line.

It will be noted also that my apparatus permits of the maintenance of a maximum volume of priming liquid ready for supply to the pump by the use of a priming liquid compartment of such form that it will occupy a minimum space with a consequent reduction of the bulk of the structure as a whole. Furthermore, the manner in which I have utilized the liquid being discharged from the impeller chamber to effect stirring of the mud and silt or other debris in the priming liquid compartment practically eliminates all danger of clogging of the pump.

It should also be noted that the provision of a priming liquid passageway in the base of the suction chamber results in certain functional advantages. In the first place, it reduces the

amount of liquid which must be maintained in the priming liquid compartment to effect priming. In the second place, it obviates danger of air being sucked into the suction chamber by a vortex of water such as tends to occur with a priming liquid passageway disposed in the upper portion of a suction chamber.

Various other features of advantage will appear from the preceding description and the claims 10 appended hereto.

Having thus described my invention, what I claim is:

1. A self-priming centrifugal pump comprising a substantially drum-shaped outer casing adapted 15 to form a compartment for priming fluid, said compartment having an outlet at its upper end, an impeller chamber disposed within said compartment and at one side thereof, said chamber being of volute form and being eccentrically disposed in said compartment, said chamber being of such a shape and size and being so positioned in said compartment that there is a substantial space beside and above it in said compartment, a discharge outlet from said chamber located at the 20 base of said compartment so that liquid discharged therefrom will undercut any sand or silt which deposits in the bottom of said compartment, the outlet from said chamber being so disposed relative to said outlet from said compartment that the major portion of the fluid discharged from said chamber will pass directly to and through said compartment outlet while a portion of the fluid will be first circulated within 25 the space beside and above said chamber, a suction chamber disposed in said space at the side of said impeller chamber and extending from the top of said compartment to a point spaced above the bottom thereof, an opening in the wall which separates said impeller chamber from the suction 30 chamber, a port for permitting flow of fluid from said compartment into said suction chamber, said port being located below the horizontal center plane of said suction chamber, an elbow member disposed over said port and adapted to direct fluid 35 through said opening, priming fluid being adapted to flow from said compartment through said port into said suction chamber and then into said impeller chamber, means for closing said port to 40 shut off flow of fluid therethrough when the pump can operate without priming fluid, said means comprising a hinged plate which initially extends down into the space below said suction chamber and which has an extension projecting 45 across the discharge outlet from said impeller chamber.

2. A self-priming centrifugal pump comprising a substantially, drum-shaped outer casing adapted to form a compartment for priming fluid, said compartment having an outlet, an impeller chamber disposed within said compartment and at one side thereof, said chamber being of such a shape and size and being so positioned in said compartment that there is a substantial space 50 left at the side of it in said compartment, a discharge outlet from said chamber located at the base of said compartment so that liquid discharged therefrom will undercut any sand or silt which deposits in the bottom of said compartment, the outlet from said chamber being so disposed relative to the outlet from said compartment that the major portion of the fluid discharged from said chamber will pass directly to and through said compartment outlet while a 55 portion of the fluid will be first circulated within

the space beside said chamber, a suction chamber disposed in said space and adapted to partially obstruct circulation of fluid through said space in said compartment, the lower end of said suction chamber being spaced from the bottom of said compartment, an opening permitting flow of fluid from said suction chamber into said impeller chamber, a port for permitting flow of fluid from said compartment into said suction chamber, said port being located below the horizontal center 10 plane of said suction chamber, means for closing said port to shut off flow of fluid therethrough when the pump can operate without priming fluid, said means comprising a swinging plate which initially extends down into the space below said suction chamber and which has an extension projecting 15 into the path of fluid discharged from said impeller chamber.

3. A self-priming centrifugal pump comprising a priming fluid compartment having an outlet 20 leading therefrom, an impeller chamber disposed within said compartment, said chamber being of such a shape and size and being so positioned in said compartment that there is a substantial space left beside said chamber in said compartment, a discharge outlet from said chamber located at the base of said compartment so that liquid discharged from said impeller chamber will undercut any sand or silt which deposits 25 in the bottom of said compartment, the outlet from said chamber being so disposed relative to the outlet from said compartment that the major portion of the fluid discharged from said chamber will pass directly to and through said compartment outlet while a portion of the fluid will be first circulated within the space beside 30 said chamber, a suction chamber disposed in said space and adapted to partially obstruct circulation of fluid through said space, the lower end of said suction chamber being spaced from the bottom of said compartment, an opening permitting flow of fluid from said compartment into said suction chamber, means for closing said port to shut off flow of fluid therethrough when the pump can operate without priming fluid, said means comprising a swinging plate which initially extends down into the space below said suction chamber and which has an extension 35 projecting into the path of fluid which is discharged from said impeller chamber.

4. A self-priming centrifugal pump comprising a priming fluid compartment, an impeller chamber disposed within such compartment, a discharge outlet from said chamber located at the base of said compartment so that liquid discharged from said impeller chamber will undercut any sand or silt which deposits in the bottom of said compartment, a suction line leading axially from said impeller chamber and having a portion thereof disposed within said compartment, a port in said portion of said suction line for permitting flow of priming fluid from said compartment into said suction line, said port being located below the horizontal center plane of said portion of said suction line, means for automatically closing said port to shut off flow of fluid therethrough when the pump can operate without the aid of priming fluid, said means comprising a swinging plate which is adapted to be forced towards closing position by the fluid flowing through the pump, said plate having an extension which projects into the path of fluid which is discharged from said impeller chamber. 70 75

5. A self-priming centrifugal pump comprising a priming fluid compartment, an impeller chamber disposed within said compartment, a discharge outlet from said chamber located at the 5 base of said compartment so that liquid discharged from said impeller chamber will undercut any sand or silt which deposits in the bottom of said compartment, a suction line leading from said impeller chamber and having a portion 10 thereof disposed within said compartment, a port in said portion of said suction line for permitting flow of priming fluid from said compartment into said suction line, said port being located below the horizontal center plane of said 15 portion of said suction line, means for automatically closing said port to shut off flow of fluid therethrough when the pump can operate without the aid of priming fluid, said means comprising a swinging plate which is adapted to be forced towards closing position by the fluid flowing through the pump, said plate having a portion which projects into the path of fluid which is discharged from said impeller chamber.
6. A self-priming centrifugal pump structure 20 comprising an impeller chamber, an impeller rotatably mounted therein, a container for priming liquid enclosing said impeller chamber, a discharge passage leading from the impeller chamber into the priming container, a suction 25 chamber disposed within said priming container and leading into said impeller chamber and adapted to be connected to a suction line, a priming port leading from said priming liquid container into said suction chamber, said priming 30 port being restricted so that a quantity of liquid, less than the capacity of the pump, will be permitted to flow therethrough, a valve for controlling said port and adapted to admit priming liquid into said impeller chamber when open and 35 to substantially exclude priming liquid therefrom when closed, said valve which controls said priming port comprising a hinged plate movable to a position where it substantially covers said priming port or to a position where it completely uncovers said port and being movable towards closed position by the velocity head of liquid discharged from said impeller chamber, said hinged plate projecting into the path of flow of liquid 40 discharged from said impeller chamber during the priming action but being movable substantially out of the path of flow by the action thereon of said velocity head when the priming action is completed, and a weight of preselected resisting power associated with said hinged plate to 45 prevent initiation of the movement thereof into the position where it covers said priming port until substantially all the air has been exhausted from the suction line and until the liquid discharged by said impeller has a selected velocity 50 head, so that the priming action will be continuous until completed, said hinged plate being so arranged that the hydrostatic pressure of the liquid in the priming compartment will be exerted over the entire lower surface thereof and 55 over the entire upper surface thereof with the exception of that portion which covers the priming port so that there will be a slight hydrostatic unbalance which tends to aid in maintaining the plate in covering relation to said port, the 60 vacuum force developed by the impeller also aiding in keeping said plate in covering relation to the port, said weight being sufficient to overcome this slight hydrostatic unbalance as soon as 65 vacuum is broken and the velocity head of liquid discharged by the impeller drops below the se-

lected amount so that the hinged plate will always uncover said port when the pump needs priming.

7. A self-priming centrifugal pump structure 70 comprising an impeller chamber, an impeller rotatably mounted therein, a container for priming liquid associated with said impeller chamber, a discharge passage leading from the impeller chamber into the priming container, a suction chamber leading into said impeller chamber and adapted to be connected to a suction line, a priming port leading from said priming liquid container into said suction chamber, said priming port being restricted so that a quantity of liquid less than the capacity of the pump will be permitted to flow 75 therethrough, a valve for controlling said port and adapted to admit priming liquid into said impeller chamber when open and to substantially exclude priming liquid therefrom when closed, said valve which controls said priming port comprising a hinged plate movable to a position where it substantially covers said priming port or to a position where it uncovers said port and being movable towards closed position by the velocity head of liquid discharged from said impeller chamber, and a weight of preselected resisting power associated with said hinged plate to prevent initiation of the movement thereof into the position where it covers said priming port until substantially all the air has been exhausted from the suction line and until the liquid discharged by said impeller has a selected velocity head, so that the priming action will be continuous until completed, said hinged plate being so arranged that the hydrostatic pressure of the liquid in the priming compartment will be exerted over the entire lower surface thereof and over the entire upper surface thereof with the exception of that portion which covers the priming port so that there will be a hydrostatic unbalance which tends to aid in maintaining the plate in covering relation to said port, the vacuum force developed by the impeller also aiding in keeping said plate in covering relation to the port, said weight being sufficient to overcome this hydrostatic unbalance and uncover 80 said port as soon as vacuum is broken and the velocity head of liquid discharged by the impeller drops below the selected amount.

8. A self-priming centrifugal pump structure 85 comprising an impeller chamber, an impeller rotatably mounted therein, a container for priming liquid associated with said impeller chamber, a suction line leading into said impeller chamber, a priming port leading from said priming liquid container for permitting passage of liquid into said impeller chamber, a discharge passage leading from the impeller chamber into the priming container, said priming port being restricted so that a quantity of liquid less than the capacity of the pump will be permitted to flow therethrough, a valve for controlling said port and adapted to admit priming liquid into said impeller chamber when open and to substantially exclude priming liquid therefrom when closed, said valve which controls said priming port comprising a hinged plate movable to a position where it substantially covers said priming port or to a position where it uncovers said port and being movable towards closed position by the velocity head of liquid discharged from said impeller chamber, and means of preselected resisting power associated with said hinged plate to prevent initiation of the movement thereof into the position where it covers said priming port until substantially all the air has been exhausted from the suction line and until the liquid 90 discharged by the impeller drops below the selected amount.

discharged by said impeller has a selected velocity head, so that the priming action will be continuous until completed, said hinged plate having opposed surfaces, one of which controls the priming port, 5 and being so arranged that the hydrostatic pressure of the liquid in the priming compartment will be exerted over the entire area of the surface which does not control the priming port and over the entire area of the surface which controls the 10 priming port with the exception of that portion which covers the priming port so that there will

be a hydrostatic unbalance which tends to aid in maintaining the plate in covering relation to said port, the vacuum force developed by the impeller also aiding in keeping said plate in covering relation to the port, said means of preselected resisting power being sufficient to overcome this hydrostatic unbalance and uncover said port as soon as vacuum is broken and the velocity head of liquid discharged by the impeller drops below the selected amount. 5
